UNITED STATES PATENT OFFICE.

EUGENE ROBERTS, OF SALT LAKE CITY, UTAH.

DEVICE FOR METERING FLUIDS.

1,247,330.

Specification of Letters Patent. Patented Nov. 20, 1917.

Application filed February 7, 1914. Serial No. 817,318.

To all whom it may concern:

Be it known that I, EUGENE ROBERTS, citizen of the United States, and resident of Salt Lake City, county of Salt Lake, State 5 of Utah, have invented certain new and useful Improvements in Devices for Metering Fluids, of which the following is a specification.

This invention relates to devices for 10 measuring a flow of fluids and is intended to overcome certain objections and difficulties that are incident to the ordinary methods of performing this work when the entire fluid body to be measured is passed directly through a measuring device.

In its essential features the invention comprises a main valved passage for the flow of the fluid combined with a by-pass which is also provided with a valve coördinated to the valve in the main passage and a registering device to measure the liquid passing through the by-pass, a fixed ratio being preserved between the volume of liquid passing through the main passage 25 and that passing through the by-pass.

These and other features of the invention will be fully described hereinafter and will be defined in the claims hereto annexed.

In the drawings:

30 Figure 1 is a vertical sectional view illustrating the preferred mode of embodying the principle of this invention;

Fig. 2 is a plan view of the main valved passage; and

35 Fig. 3 is a cross-section of the valved by-pass.

In the practice of my invention according to the form illustrated in the drawings I provide a casing *a* formed with an inlet 40 *a'* to which the water supply pipe is conveniently attached and with an outlet passage *a''* for attachment to the outlet pipe. Within the casing is mounted an annular valve chamber *b* whose inner wall is provided with vertical grooves *b'* which increase in depth and width to the top and disappear at the extreme bottom of the valve chamber.

The valve *C* is an ordinary type of piston 50 valve normally seated upon the valve seat *b'* to completely close the passage against the flow of liquid. Obviously if the outlet pipe is opened the pressure of the water in the outlet passage *a''* will be diminished so 55 that the valve will be raised from its seat

by the greater pressure of the water beneath it. Obviously the farther the valve piston is lifted from its seat the greater will be the flow of water through the valve chamber owing to the increasing size of the 60 passage toward the top. When the outlet is closed the pressure in passage *a''* becomes equal to the pressure in the passage *a'* and the valve is returned to its seat by means of the piston rod *c'* which is actuated by a 65 series of removable weights *x*, or the like to restore the valve to closed position.

In the lower part of the casing is placed an adjustable outlet pipe *d* having a series of tapered ports or openings at *d'* which are 70 normally closed by a tubular valve *e* when the valve *C* is in closed position. This slide valve *e* is connected by the extension arm *e'* with a slotted bell crank lever *e''* mounted in a bracket *e'''* whose other slotted arm is 75 connected with the rod *c'* extended downward from the piston *C*.

Obviously when the valve *C* is lifted from its seat this motion is transmitted through the bell crank lever to the slide valve *e* so 80 as to uncover the ports *d'* in the by-pass pipe *d*. The ports *d'* are graduated to correspond to the tapered passages in the valve chamber *b* so that as the upward movement of the piston *C* continues to increase the 85 available opening for the flow of liquid the corresponding uncovering of the ports *d'* produces a corresponding increase in the capacity of the by-pass ports *d'*.

In order to properly regulate or adjust 90 the relative capacities of the respective valved passages affected by the movements of their respective valves, I provide for adjustment of the connections between the two valves which may be of any suitable type. 95 In this case the bracket *e'''* which forms the fulcral support of the bell crank lever *e''* is made adjustable by mounting it to slide in suitable retaining brackets *e''* on the inside of the casing, said bracket being engaged 100 by an adjusting screw *e'''* which projects through a properly packed aperture in the wall of the casing in order to render it accessible to the attendant. Obviously according to the arrangement shown, as the 105 bracket *e'''* is lowered the distance between the center of the lever and its point of engagement with the extension *e'* of the slide valve is shortened relative to the length of the power arm of said lever so as to vary the 110

relative lengths of traverse of the two valves. At the same time the by-pass pipe d is itself adjustably set in the casing by means of a screw threaded connection as shown at d^3 so that it may be adjusted to proper relationship with the slide valve e . By means of the pipe d^4 the pipe d is connected with any suitable type of water register or meter shown at d^5 through which the liquid passes into the return pipe d^6 which delivers it into the outlet passage a^2 .

In order that the device may be adapted for use in registering very hot liquids which would otherwise affect the accuracy of the meter I insert a cooling coil f through which the liquid entering the by-pass may be circulated before passing into the meter d^5 . The direct circuit to the meter or the indirect circuit through the cooling coil is controlled by the valves f' , d^7 so that the cooling coil can be cut out or cut in to the circuit whenever desired.

By constructing and arranging the valve mechanism so that a constant ratio is maintained between the volume of liquid flowing through the main valve chamber b and that flowing through the by-pass d the meter can be made to register accurately the whole amount of liquid whether the liquid is flowing to the full capacity of the conduit or whether only a slight amount of liquid is passing through and this maintenance of a constant ratio between the main flow and the by-pass flow is the characteristic feature of this invention.

It will be noted that I have not undertaken to show details as to packings and stuffing boxes which would be within the province of the ordinary mechanic.

40 What I claim is:

1. The combination with the main valve chamber provided with tapered ports, a by-passage provided with correspondingly tapered ports, a valve piston seated in said valve chamber and actuated automatically by the pressure of the liquid, a by-passage valve for controlling the by-passage ports, means for regulating the action of the by-passage valve in accordance with the movement of said first mentioned valve, the by-passage being adjustable in relation to its valve, substantially as described.

2. The combination of the valve chamber provided with a set of graduated ports to increase its capacity for flow of liquid according to the extent of traverse of the valve, a by-passage having a set of correspondingly graduated ports, a valve controlling each set of ports, means for operatively connecting said valves, a fluid meter connected with said by-passage and a cooling conduit

connected with the by-passage in advance of the meter, substantially as described.

3. The combination of the main passage provided with a graduated valve chamber, 65 an automatic regulating valve seated therein, a by-passage and a fluid meter connected therewith, and means controlled by said valve for regulating the admission of fluid through the by-passage in a constant ratio 70 to the volume of fluid passing through the main passage, substantially as described.

4. A fluid-measuring device embracing in its construction a casing provided with inlet and outlet ports, a valve chamber provided with internal grooved tapering ports, an automatic valve piston mounted therein, a supplemental by-pass pipe arranged within said casing and provided with tapered ports, a slide valve for controlling said 80 ports, an adjustable lever forming an actuating connection between the two valves and means for adjusting said lever to vary the relative traverse of one valve to the other, and a meter connected with said by-passage 85 pipe, substantially as described.

5. In a water meter, the combination of the main valved passage for the flow of water, a reciprocatory pressure-actuated valve for controlling and regulating the 90 flow through said passage, a by-passage, a reciprocatory valve for controlling and regulating the flow of water through said by-passage in correspondence to the flow through the main passage, means connected with and actuated by the main passage valve for operating the by-passage valve, and means whereby said connecting means may be adjusted to vary the length of traverse of the by-passage valve, substantially as described.

6. The combination with the main passage provided with a port having peripheral grooved passages gradually increasing in capacity from the valve seat outward, a 105 pressure valve mounted therein for controlling the flow of water therethrough, a by-passage, a graduated valve mounted therein to vary the capacity of said by-passage, and intermediate connections by which the capacity of the by-passage is varied in proportion to the capacity of the main passage as the valve in the main passage port moves from its seat, said connections being adjustable to secure proper correlation, 110 substantially as described.

In witness whereof, I have subscribed the above specification.

EUGENE ROBERTS.
